US0D1074580S

(12) **United States Design Patent** (10) **Patent No.:** **US D1,074,580 S**
(45) **Date of Patent:** **** May 13, 2025**

(54) **POWER SOURCE**

(71) Applicant: **Shenzhen Weiku Chuangxin Technology Co., Ltd**, Shenzhen (CN)

(72) Inventor: **Wei Xiao**, Shenzhen (CN)

(73) Assignee: **Shenzhen Weiku Chuangxin Technology Co., Ltd**, Shenzhen (CN)

(**) Term: **15 Years**

(21) Appl. No.: **29/877,288**

(22) Filed: **Jun. 5, 2023**

(30) **Foreign Application Priority Data**

Dec. 22, 2022 (CN) 202230854830.6

(51) **LOC (15) Cl.** **13-02**

(52) **U.S. Cl.**

USPC **D13/103**

(58) **Field of Classification Search**

USPC D13/103, 107, 108, 110, 118, 119, 184,

D13/199

CPC H02J 7/0013; H02J 7/0042; H02J 7/0045;

(57) **CLAIM**

The ornamental design for a power source, as shown and described.

DESCRIPTION

FIG. 1 is a front perspective view of a power source, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the power source, which form no part of the claimed design.

1 Claim, 8 Drawing Sheets
